UNITED STATES PATENT OFFICE.

LEE R. MILLER AND EMANUEL T. RICHERT, OF AKRON, OHIO.

DESIGN FOR A BILLIARD-CUE HEAD.

SPECIFICATION forming part of Design No. 33,207, dated September 18, 1900.

Application filed August 16, 1900. Serial No. 27,115. Term of patent 7 years.

To all whom it may concern:

Be it known that we, LEE R. MILLER and EMANUEL T. RICHERT, residing in Akron, in the county of Summit and State of Ohio, have 5 invented and produced a new and original Design for Heads for Billiard-Cues, of which the following is a specification, reference being had to the accompanying drawings, forming part thereof.

10 In the drawings, Figure 1 is a perspective elevation of our new design in billiard-cue heads, looking somewhat upward from the stem to or into the head proper; and Fig. 2 is a plain side elevation of the head complete.

15 As thus shown in the drawings, the leading or material feature of the design consists, essentially, of the shape and surface configuration thereof, distinguished by certain peculiar features which especially mark its appearance and characterize the design. These

features comprise the substantially semi-spherical head 2, with an evenly-rounded exterior surface, and the stem 3, with graduated annular enlargements 4 and 5 at its base, of which the enlargement 5, especially, is within 25 head 2, and a channel extending entirely around said enlargement 5 within the lower portion of head 2, as defined by its rim 6. The stem 3 is ornamented by a rib 7, spirally entwined about it below the enlargement 4. 30

What we claim is—

The design for a billiard-cue head, substantially as shown and described.

Witness our hands to the foregoing specification this 11th day of August, 1900.

LEE R. MILLER.

EMANUEL T. RICHERT.
